UNITED STATES PATENT OFFICE.

CHARLES E. FOOTE, OF NUNDA, NEW YORK, ASSIGNOR TO THE FOOTE COMPANY, OF NUNDA, NEW YORK, A CORPORATION OF NEW YORK.

POWER-OPERATED DISCHARGE MECHANISM FOR CONCRETE-MIXERS.

1,394,161.

Specification of Letters Patent.

Patented Oct. 18, 1921.

Application filed October 1, 1920. Serial No. 414,066.

To all whom it may concern:

Be it known that I, CHARLES E. Foote, a citizen of the United States, residing at Nunda, in the county of Livingston and State of New York, have invented certain new and useful Improvements in Power-Operated Discharge Mechanism for Concrete-Mixers, of which the following is a specification.

10 My invention relates to a new and useful improvement in power operated discharge mechanism for concrete mixers and has for an object to provide a device that is extremely simple in construction and exceedingly efficient in operation.

In a separate application filed of even date herewith bearing Serial No. 414,065 I have shown the operating mechanism in conjunction with a rotatable discharge chute 20 that is wherein the inner end of the chute is swung laterally of the drum of the mixer to its operative and inoperative positions while in the present application a pivotal chute adapted to be swung into and out of the drum of the mixer is provided, so that when the chute is swung outwardly of the drum of the mixer it will be in its inoperative position, and when swung inwardly of the drum of the mixer it is in a position to 30 catch the falling materials and discharge the mixer.

As is well known to those familiar with the art, extraneous means have to be provided for discharging the mixer which is 35 generally some form of chute, that is where the drum is not tilttable, and this means is generally operated manually and necessitates quite some effort on the part of the operator.

40 An object of my invention therefore is to provide a discharge mechanism that is operated wholly by power derived from the engine of the mixer, it being simply necessary to move or operate a hand lever, there- 45 by bringing certain parts into coöperation with a constantly revolving gear which will automatically swing the discharge chute outwardly to its inoperative position or will swing the chute inwardly and upwardly of the drum of the mixer to its operative or discharging position.

Still another object of my invention is to provide a chute that is supported at one end by a yoke that is provided with slots 55 therein through which passes an offset bar,

to which bar is connected a rack that is thrown into contact with a gear so that when the rack is elevated the forward end of the chute will be elevated and on a lowering of the rack the chute will be swung inwardly to its discharging position. 60

With these and numerous other objects in view, my invention consists in certain new and novel constructions and combinations of parts as will be hereinafter more fully 65 described and pointed out in the claims.

In the drawings showing a preferred form of my invention:

Figure 1 is a front view of a portion of a mixer and the power operated discharge 70 mechanism, the chute being shown in its operative or discharging position;

Fig. 2 is a side elevation, showing a portion of the mixer, the discharge chute and supporting yoke also being shown in dotted 75 lines swung to its inoperative position;

Fig. 3 is a similar view after the parts have been moved to swing the chute to its inoperative position: and

Fig. 4 is a sectional view of the yoke, a 80 portion of the drum of the mixer, and a portion of the discharge chute.

It might be here mentioned that only that much of the mixer is shown as thought necessary to illustrate the location and operation 85 of the discharge mechanism.

Referring now more in detail to the several figures there is shown a supporting beam 1, two standards or uprights 2, a top beam 3, a cross plate 4, and a mixing drum 90 supported on the usual rollers 6. The drum is provided with the usual ring gear 7, to be driven by another gear 7' that is mounted on the stub shaft 8 which shaft is mounted in a suitable bearing 8'. The main 95 countershaft 63 is shown which is suitably mounted in the bearing 64 and on the end of which is the pinion 65 which meshes with the gear 7' mounted on the stub shaft 8. The small stub shaft 8 therefore is driven at all 100 times that the mixer is in operation, and on the end of this countershaft 8 is the small gear 9 that operates the discharge chute as will be shortly described.

On the cross plate 4 are formed the bearings 10 in which is mounted the pintle 11 and secured to this pintle is the support or yoke 12 in which is secured the forward end of the discharge chute 13.

This chute when swung in or as shown in 110

Figs. 1 and 2 will catch the tumbling material as it falls from near the top of the revolving drum and discharge the same, while if the chute is swung outwardly as shown by the dotted lines (Fig. 2) the material will continue to rise and fall in the drum and of course not coming into contact with the chute will be mixed until the chute is again swung inwardly.

10 Referring now to the mechanism and manner of swinging this chute, it will be noticed that the yoke 12 is provided with the enlarged portions 14 in which are provided the slots 15.

15 Mounted in the bearings 16 on the plate 4 is the rod 17 which is provided with the offset portion 18, the offset portion extending through the aforementioned slots 15. A further bearing 19 secured to the upright 2 further supports this rod 17 and on the end of the rod is shown the arm 20.

20 Pivotedly secured to the outer end of this arm 20 is the short connecting rod 21 which is pivotally fastened at its lower end to the lug 22 formed at the upper end of a rack 23.

This gear rack is provided with the sets of teeth 24 and 25 which are disposed on the opposite sides of the rack and in staggered relation to each other, there being sufficient room between the teeth 25 and the top of the rack and between the teeth 24 and the bottom of the rack to permit the gear to revolve freely when the rack is in its either extreme position.

30 On the one side of the rack 23 is the pivotal clamp 26 which is slidably mounted on the vertically extending slide bar 27 which is slightly bent as at 28 and is secured at its upper end to the arm 29 of the operating lever 30 that is mounted in the bracket 31 on the upright 2.

The lower end of the slide bar 27 is pivoted to the link 32 that in turn is pivoted 40 to the lug 33 fastened on the beam 1. By pivoting this lower end of the slide bar to the link as shown the gear will be held in proper mesh with the teeth on the rack when the operating lever is manipulated. It is to be noted that the rack is of such length and the number of teeth is such that a movement of the rack from its one limit to the other caused by the revolution of the gear 9 will just swing the chute from its operative to its inoperative position or vice versa.

45 The operation is simple and is as follows:

Supposing that the mixer is in operation, that is material is being mixed in the drum 60 and it is desired to discharge the same. The several parts will be in the position as shown in Fig. 3. A pull of the operating lever 30 rearwardly will force the slide bar and rack slightly upwardly and inwardly so that the teeth 25 will mesh with the gear 9 which

will force the rack downwardly, which in turn pulls the arm 20 downwardly, the arm revolving the rod 17 and offset portion 18 which is within the slots 15, thus pulling in the yoke 12 and the chute 13 so that the chute extends up into the drum and beneath the tumbling mixture which as it falls in the chute will be discharged by gravity from the same.

To return the chute to its inoperative position the operating lever 30 is pushed forwardly again so that the other set of teeth 24 will engage the gear 9, when the rack will again be raised and through its connections with the rod 17 the yoke will be forced outwardly swinging the chute to its inoperative position.

From the foregoing it will be seen that I have provided a means for operating by power a discharge chute that may be quickly 85 swung to an operative or inoperative position as desired, it taking but little effort on the part of the operator, necessitating in fact only the operation of a handle or lever.

It is to be understood that changes might 90 be made in the way the chute is pivoted or the arrangements of the different parts without in any way departing from the spirit and scope of the invention.

Having thus described my invention, what 95 I claim as new and desire to secure by Letters Patent is:—

1. A power operated discharge mechanism for concrete mixers comprising a discharge chute, pivotally supported so that the same will swing inwardly and outwardly of the drum of the mixer, a rotating gear, a rack coöperating with said either gear and means for forcing one side of the rack in mesh with the gear to thereby swing the chute inwardly of the mixer to its operative or discharge position, and to the other side of the rack for swinging the chute outwardly of the drum of the mixer to its inoperative position.

110

2. A power operated discharge mechanism for concrete mixers comprising a discharge chute, swingingly mounted, a revolving gear, a rack coöperating with said rotating gear, means for moving the rack so that the said gear will be in mesh with the teeth on one side of the rack to elevate the rack and to swing the inner end of the chute downwardly and outwardly of the mixer to its inoperative position and for moving the rack 105 so that the said gear will mesh on the opposite side thereof to thereby lower the rack and swing the inner end of the chute upwardly and inwardly of the drum to its operative position.

115

3. A power operated discharge mechanism for concrete mixers comprising a discharge chute, a pivotally mounted yoke supporting said chute, said yoke provided with a slot, a rod provided with an offset portion extend-

125

130

ing through said slot, a continuously revolving gear, a rack normally out of contact with said gear, a lever connected to said rod and to said rack and means for forcing 5 the rack into contact with said gear to thereby swing the chute to either its operative or inoperative position.

4. A power operated discharge mechanism for concrete mixers comprising a discharge 10 chute extending up within the drum of the mixer, a pivotally mounted yoke supporting said discharge chute, said yoke provided with slots near its upper ends, a rod mounted at the side of the chute said rod provided 15 with an offset portion extending through the slots in the yoke, an arm mounted at the end of said rod, a continuously revolving gear, a sliding gear rack connected to said arm and provided with sets of teeth on 20 its opposite sides, means for forcing the teeth on one side of the rack into contact

with the said gear to thereby elevate the rack and swing the yoke and chute to its inoperative position and to force the other set of teeth into contact with said gear to 25 lower the rack and swing the chute to its operative position.

5. A power operated discharge mechanism for concrete mixers comprising a discharge chute, supported at one end and extending 30 within the drum of the mixer, a rotatable gear, a rack, an arm connected to said chute, means for forcing the rack into coöperation with said gear to raise the rack and said arm to thereby swing said chute outwardly to 35 its inoperative position and to lower said rack to swing the chute inwardly and upwardly of said drum to its operative position.

In testimony whereof I affix my signature. 40

CHARLES E. FOOTE.
